his Attorney.

UNITED STATES PATENT OFFICE.

ALFRED C. STEWART, OF PASADENA, CALIFORNIA.

ROTARY PUMP.

Application filed August 6, 1923. Serial No. 656,138.

This invention relates to an apparatus for use in pumping vapors, gases, or liquids and the main object of the invention is to provide a pump which will present the advantages in regard to simplicity in construction and operation of a rotary pump while at the same time avoiding the difficulties of packing of the working piston which are usually present in rotary pumps.

Another object of the invention is to provide a pump which is especially adapted to be driven by motors such as single phase alternating current motors having small starting torque, the pump being of such construction and operation that effective load or resistance is not developed thereby until a considerable speed is obtained. Other objects of the invention will appear hereinafter.

The accompanying drawing illustrates an embodiment of my invention and referring thereto:

Fig. 1 is a transverse section of the pump.

Fig. 2 is a longitudinal section thereof.

Fig. 3 is a partial plan view of the shaft for the pump, showing the valve ports therein.

The pump shown in the drawing is mounted on a base or frame 1 carrying a standard 2 which supports a stationary shaft 3 on which the pump members are mounted to rotate, the said shaft being held in stationary or nonrotative position by any suitable means. I prefer to provide the shaft 3 with longitudinal bores or passages 4 and 5 through which the fluid to be pumped is supplied to and delivered from the pump as hereinafter described. A rotary member or carrier 6 is mounted to rotate on the stationary shaft 3 and is provided with any suitable driving means, for example, a pulley 7 mounted or formed thereon, said rotary carrier being also provided or formed with any desired number of cylinders 8 extending radially with respect to the axis of rotation of said rotary carrier. In the drawing two of said cylinders are shown but it will be understood that any desired number may be used, it being preferred however in any case to so position the cylinders as to balance the weight thereon around the axis of rotation as far as possible. Each cylinder 8 is provided with an inlet port 9 adapted to register with an inlet port 10 in the wall of the hollow shaft 3 and connecting with the inlet passage 4 aforesaid, such registration being effected during a portion only of the rotation of the rotary carrier. Each cylinder is further provided with an outlet port 11 adapted to register during a portion of the rotation of the carrier with an outlet port 12 in the wall of the hollow shaft 3 communicating with the outlet passage 5 in said shaft. The aforesaid inlet and outlet ports are so positioned that the times of registration of the inlet passage for any cylinder take place at periods between the times of registration of the outlet ports for said cylinder, so that each cylinder is connected alternately to the inlet passage and to the outlet passage. A piston 13 is mounted to slide in each of the cylinders 8, such piston being provided if necessary with packing rings or other means for maintaining sufficiently tight engagement thereof with the walls of the cylinder to prevent any substantial leakage of fluid between such parts. Each piston is further provided with a thrust pin or member 14 which is fitted loosely in a recess or socket 15 in the piston and is adapted to engage at its outer end with a cylindrical eccentric face 16 on a rotary controlling or eccentric member 17 which is mounted to turn on the standard 2 around an axis of rotation which is concentric with cylindrical cam face 16, but is eccentric to the axis of rotation of the rotary member 6. The recess 15 is of sufficient width to allow a slight tilting movement of the thrust member 14 and the inner end of said thrust member is preferably rounded or tapered to fit the corresponding rounded or tapered inner end of said socket or recess to provide for such tilting movement. The rotary eccentric member 17 rotates freely upon a bearing means 18 shown as a ball bearing mounted on the stationary shaft 3, but with its axis displaced from the axis of said shaft by a distance equal to one half of the required piston stroke. As shown in Fig. 2, the eccentric controlling member 17 is preferably mounted beside the rotary carrier member 6 at the opposite side from the driving means or pulley 7 and encloses said carrier member only at such side and at its peripheral surface. By such a construction the device may be conveniently dismantled and assembled, as the rotary carrier member,

together with the pistons and thrust members carried thereby, may be easily withdrawn from or inserted within the eccentric controlling member.

5 The operation of the pump is as follows: Rotary member 6 is set into rotation by means of the pulley 7 or other motive device, and the cylinders 8 are caused to revolve around their axis of rotation, and assuming that the pump is working at its normal speed the rotation of the said member 6 will be sufficiently rapid to cause the pistons 13 to always move outwardly as far as is permitted by engagement of the thrust member 14 with the inner face of the eccentric member 17. The said eccentric member will rotate freely with the carrying member 6 but on a different axis of rotation and the pistons 13 will therefore move inwardly and outwardly in their respective cylinders. Thus with the arrangement shown in the drawing in which the axis of rotation of the cylinders is displaced above the axis of rotation of the eccentric member, the cylinders 25 will be thrust inwardly by operation of the eccentric member on the thrust pin of each cylinder as it approaches the uppermost portion and then as the cylinder passes toward the lowermost portion the piston therein will 30 be thrust outwardly by centrifugal action to an extent which is limited by the engagement of the thrust pin with the eccentric face 16. While therefore the respective cylinders and pistons rotate as a whole each piston is given a radially reciprocating movement in its cylinder resulting in compression of the fluid within the cylinder when the piston is moving inwardly and expansive or suctional action when the piston 35 is moving outwardly, the valve ports or inlet and outlet ports 8, 9, and 10, 11 being so positioned that in the rotation of the cylinders on the stationary shaft each cylinder is brought into communication with the inlet passage 4 while the piston therein is moving outwardly and is brought into communication with the outlet passage 5 while the piston therein is moving inwardly.

It will be noted that when the pump is 40 started into operation, for example, by an electric motor, the only load on the motor is that due to friction of the parts as each piston when it is pushed in by the eccentric means remains in such retracted position and no work is done in the rotation of the carrying member 6 except that due to friction of the parts. As the speed of the rotary member 6 increases and approaches that required for normal operation the centrifugal 45 action on the pistons is sufficient to force them outwardly to an extent determined by the operation of the eccentric means and this operation results in pumping of fluid and represents an increase in the amount of work 50 done by the motor. Certain motors of the

single phase type are adapted to carry a normal working load when at or near full speed but have but little starting torque and the pump described is therefore especially adapted for use with such motors. It is also well adapted for use with gasoline engines or other power devices which can not be started under load and in connection with such power devices the use of any clutch means may be dispensed with.

In the above described operation the rotary controlling or eccentric member 17 is carried around by the frictional contact thereof with the thrust member 12 and any slippage of the parts required by reason of the eccentricity of the rotation of the said controlling member with respect to the rotation of the cylinders is provided for by the loose mounting of the thrust pins 14 which tilt one way or the other in the recesses 15, 80 these thrust pins adapting themselves in all circumstances either by sliding on the inner eccentric face 16 or by tilting in their sockets formed by the corresponding recesses 15. In so far as there is any slippage of the thrust 85 members on the rotary controlling member 17 the latter acts as an eccentric by operation of the cylindrical eccentric 16 thereof on the thrust members and as a matter of fact the pump will be operated even if the member 17 is held from rotation, the cylindrical face thereof being eccentric to the action of rotation of the carrier member so that it will operate upon the thrust pins to force the pistons radially inward as the corresponding 90 cylinders approach that portion of the cylindrical eccentric face which is closer to the axis of shaft 3. Such operation however involves considerable friction and it is preferred to mount the controlling member 17 95 so as to provide for rotation thereof with minimum friction and when it is so mounted the thrust members will generally maintain a substantially unchanged point of contact with the controlling member without any considerable amount of sliding motion.

What I claim is:

A pump comprising a stationary shaft provided with inlet and outlet passages and with valve ports communicating with said passages, a carrier member mounted to rotate on said shaft and provided with driving means connected thereto at one side thereof and with a plurality of radially extending cylinders, and said carrier member having 115 valve ports adapted to alternately establish connection from each cylinder to said inlet and outlet passages, pistons mounted to operate radially in the respective cylinders and adapted to move outwardly therein by 120 centrifugal action, thrust members for the respective pistons, and a controlling member 125 rotatably mounted beside said carrier member at the opposite side from said driving means, said controlling member enclosing said carrier 130

member only at such opposite side and at the peripheral surface thereof so as to permit said carrier member, together with the pistons and thrust members, to be freely moved axially into and out of position to be so enclosed, and said controlling member being provided with a cylindrical face eccentric to

said shaft and adapted to engage said thrust members to force the respective pistons inwardly.

In testimony whereof I have hereunto subscribed my name this 24th day of July, 1923.

ALFRED C. STEWART.
